UNITED STATES PATENT OFFICE.

FRANK BLANKAVAG, OF PRINCETON, WISCONSIN.

LOCK.

1,221,132.

Specification of Letters Patent.

Patented Apr. 3, 1917.

Application filed July 22, 1915. Serial No. 41,302.

To all whom it may concern:

Be it known that I, FRANK BLANKAVAG, a citizen of the United States, residing at Princeton, in the county of Green Lake and State of Wisconsin, have invented certain new and useful Improvements in Locks; and I do declare the following to be a full, clear, and exact description of the invention, such as will enable others skilled in the art to 10 which it appertains to make and use the same.

My invention relates to useful improvements in locks and latches, and more particularly to the former, the object of the invention being to provide a lock having in addition to its main key actuated locking bolt, a supplemental bolt which is normally held retracted against the tension of a spring, but which is immediately projected 20 upon attempted retraction of the main bolt.

With the above object in view, the invention resides in certain novel features of construction and in unique combinations of parts to be hereinafter fully described and 25 claimed, the descriptive matter being supplemented by the accompanying drawings which constitute a part of this application and in which:

Figure 1 is an elevation, on a small scale, 30 showing the inner side of a portion of a door equipped with the improved lock;

Fig. 2 is a similar view on an enlarged scale with the cover plate of the lock removed and illustrating the lock keeper in 35 vertical section;

Fig. 3 is a similar view showing a different position of parts;

Fig. 4 is a detail vertical section taken on the plane indicated by the line 4—4 of 40 Fig. 1;

Fig. 5 is a perspective view of the supplemental locking bolt;

Fig. 6 is a similar view of the tumbler thereof;

Fig. 7 is an additional perspective showing the tumbler releasing trigger; and,

Fig. 8 is a disassembled perspective view of the keeper.

In describing the invention, I shall refer 50 to the drawings by similar reference characters placed on corresponding parts throughout the several views, the numeral 1 designating broadly a casing which is preferably though not necessarily, of rectangular form 55 having an appropriate cover plate 2, the lower edge of the casing being provided

with a notch 3 through which an appropriate shiftable stop 4 may be projected into the casing for a purpose to be set forth, such stop being carried by a stem 5 which projects through a slot 6 in the cover plate 2 and which is provided with an appropriate operating button 7 and with a spring 8 interposed between said button and the cover plate and having offset ends adapted to 60 spring into grooves 9 in the outer side of said plate, when the stop is shifted either to active or inactive position.

Slidably mounted in the upper end of the casing is a spring projected catch 10 which 70 may be of any preferred formation capable of being retracted by partial rotation of the usual knob actuated shaft 11, while immediately below the catch 10, is a key projected and retracted locking bolt, this bolt being 75 normally held against movement by a common type of spring pressed tumbler 13, but being operable in either direction by a key 14 which is insertible through peculiarly shaped key holes 15 in opposite sides of the 80 casing. These key holes are here shown as elongated and having their opposite ends enlarged as disclosed at 16 and 16^a for the reception of the usual cylindrical projection on the key.

The enlarged end 16 of either key hole receives the projection on the key when the bolt 12 is to be projected or retracted, whereas the end 16^a receives said projection when a supplemental bolt 17 is to be retracted. 90

The bolt 17 is disposed immediately above the notched lower side of the casing 1 and is provided with a pair of stop shoulders 18 on its upper side which receive therein a stop 19 which is extended laterally from a substantially right angular tumbler 20, the latter being pivoted at one end to a stud 21 spaced upwardly from the bolt, while its opposite end is provided with a laterally extending shoulder 22, the intermediate portion of the 100 tumbler being positioned behind the aforesaid bolt with its stop 19 disposed between the stop shoulders 18, this lowermost position of the tumbler being effective to retain the bolt 17 retracted against a coiled spring 105 23 which is interposed between the rear side of the casing and a shoulder 24 depending from the bolt, by an appropriate leaf spring 25 which bears normally against the aforesaid stop.

Pivoted at one end upon a stud 26 is a trigger 27 whose other end is forked as dis-

closed at 28 and is positioned in the path of the key 14 when the latter is used to retract the main locking bolt 12, the intermediate portion of the aforesaid trigger being disposed in contact with the shoulder 22.

By this positioning of parts, when the key 14 is inserted into the upper end 16 of one of the key holes and turned in a direction to retract the main locking bolt 12, the forked end of the trigger will be encountered by the wing of the key which is fashioned similarly to said forged end. The result is that the trigger 27 is raised, thus so rocking the angular tumbler as to retract its stop 19 from contact with the stop shoulders 18, whereupon the coiled spring 23 immediately projects the supplemental bolt 17, which latter is therefore effective before the main bolt 12 is withdrawn.

When the supplemental bolt is to be retracted, the key is inserted with its projection in the lower end 16^a of one of the key holes 15, whereupon its wing may be brought into contact with a shoulder 29 on said bolt thus readily allowing the same to be withdrawn. If desired, additional tumbler means may be provided for retaining the supplemental bolt in projected position, but it is not thought necessary to encumber the present application with illustration of such means, particularly in view of the fact that an alarm is operated by projection of the bolt in question, thus giving warning to the occupants of the building that attempts are being made to enter the same, it being therefore unessential to provide the tumbler means in question, since by the time the supplemental bolt is retracted and the door is open, the occupants of the building will undoubtedly be aroused and prepared to resist entrance.

During the periods when use of the supplemental bolt 17 is unnecessary, however, the shiftable stop 4 is projected in advance of the shoulder 24, thus preventing projection of said bolt regardless of motion imparted to the trigger 27 by the movement of the key inserted to actuate the bolt 12.

Secured by screws or the like 30 to the inner side of the door frame, is an upright face plate 31 in rear of which a housing 32 is positioned, said housing being L-shaped in transverse section and having rectangular ends 33 one of whose free edges abuts the rear face of the aforesaid face plate, stops 34 being carried by said plate in contact with the ends 33, whereby to limit vertical movement of the housing, horizontal movement of the latter being resisted in one direction by said stops, and in other directions by the walls of the cavity in which the housing is inset.

By the construction just described, the keeper is provided with one open side disposed toward the door and adapted to re-

ceive therein the ends of the catch 10, the bolt 12, or the supplemental bolt 17 when these parts are projected.

Pivoted within the housing at one end, is a switch arm 35 which is provided at its other end with a lateral extension 36 adapted to be presented to the contacts 37 when the supplemental bolt 17 is projected, said arm being normally held by the friction of its pivot, in the position shown in Fig. 2. By this means, the circuit of an electric alarm may be completed, since the pivoted end of the switch arm 35 is connected by the wire 38 with a binding post 39 on the inner side of the face plate 31, while the contacts 37 are connected by a wire 38^a with an additional binding post 39^a positioned adjacent the post 39. Thus it will be evident that by appropriate wiring either a visual or audible alarm may be operated simultaneously with projection of the supplemental locking bolt, or in other words upon an attempt to unlock the door.

When the use of the circuit closing device is not needed, a button 40 adjacent the inner side of the face plate 31 may be rotated thereby so disposing an arm 41 in rear of the switch arm 35 as to prevent disposition of the latter to use.

The switch arm 35 may be constructed in any one of a number of types, but it is preferably formed of one flat strip of copper or other appropriate metal, the pivoted end of the strip being offset at 35^a, while between its ends said strip is bent laterally at 35^b, and is then continued longitudinally and bent laterally in the opposite direction at its free end to provide the extension 36. Since the opposite end portions of the strip forming the arm 35 must lie in planes disposed at right angles to each other, the portion of said strip between the offset portion 35^a and the lateral bend 35^b is given a quarter twist as shown at 35^c. By constructing the arm in the manner above set forth, the same may be easily and cheaply manufactured, yet will be efficient and durable in operation, the portion of said arm continuing from the bend 35^b, becoming advantageous to receive therein the arm 41.

From the foregoing description, taken in connection with the accompanying drawings, it will be evident that although I have provided comparatively simple and inexpensive construction for the attainment of the results desired, the invention will be efficient, durable, and reliable, these being salient features in any article of manufacture.

I claim:

1. A lock comprising a key actuated locking bolt, a supplemental normally retracted spring projected locking bolt having a stop, an angular tumbler pivoted independently of the bolt and having a stop normally con-

tacting with the aforesaid stop to prevent projection of the supplemental bolt, a shoulder on said tumbler, and an inert one-piece key actuated trigger pivoted independently 5 of the tumbler and having one end disposed in the path of a false key which may be used in an attempt to retract the main bolt, the shoulder of the tumbler being disposed in the path in which the trigger moves when 10 actuated by such a key.

2. A lock comprising a casing, a main key actuated locking bolt slidably therein, a supplemental normally retracted spring projected locking bolt also mounted slidably in 15 the casing parallel with the other bolt, an L-shaped tumbler pivoted at one of its ends to the casing between the bolts and having its other end directed laterally to form a shoulder, a stop projecting laterally from 20 said L-shaped tumbler at approximately the angle thereof, another stop on the sup-

plemental bolt for coöperation with the first named stop to retain this bolt normally retracted against the tension of its spring, a one-piece trigger pivoted at one end to the 25 casing between the angularly related ends of the tumbler, said trigger extending across the end of said tumbler equipped with the shoulder and having its free end disposed in the path of a false key which may be used 30 in an attempt to retract the main bolt, said shoulder being disposed on the path upon which said trigger moves when actuated by such a key.

In testimony whereof I have hereunto set 35 my hand in presence of two subscribing witnesses.

FRANK BLANKAVAG.
